UNITED STATES PATENT OFFICE.

FELICE FRANCESCO LARIVEL, OF BATH, ENGLAND.

MACHINERY FOR DYEING AND TREATING TEXTILES.

Application filed April 14, 1919. Serial No. 289,980.

To all whom it may concern:

Be it known that I, FELICE FRANCESCO LARIVEL, a subject of the King of Italy, residing at Bath, in the Kingdom of England, have invented new and useful Improvements in Machinery for Dyeing and Treating Textiles, of which the following is a specification.

This invention relates to improvements 10 in machines for dyeing or otherwise treating hanks of yarns, slubbing and other textiles, in which the material undergoes the desired treatment immersed in the liquor. The object of the invention is to provide an 15 effective mechanical means which, besides securing a constant stirring of the bath, causes the material to be raised off the sticks by sudden falling contact with the liquor, whereby a complete uniformity of treatment 20 is obtained.

According to the present invention a frame, suspended in a dye vat and carrying the hanks of fibre or the like either on sticks, rollers or in a closed perforated cage, and partly immersed in the liquor and partly out, is first 25 mechanically reciprocated up and down, the upward movement taking place at a different speed than the downward movement, and then the motion is changed so that the said 30 frame or cage is longitudinally reciprocated to and fro in the vat, in contradistinction to such machines in which the hank carrying frame remains stationary immersed in the liquor, or is moved uniformly and simultaneously 35 in both vertical and horizontal directions.

The mechanism for reciprocating the frame up and down may be combined with means to hoist the frame clear of the vat 40 when it is desired to remove or replace the sticks carrying the fibre.

The invention is more particularly described with reference to the accompanying drawings, in which:

45 Figure 1 is a plan view of the device in one form; Fig. 2 is a corresponding side elevation.

A vat 1 of any usual form is mounted adjacent to the driving mechanism supported on 50 standards 2. A frame 3 is suspended within the vat 1 by means of a rope 4 passing over pulleys 5. The frame 3 is recessed at its sides as at 6, to receive the sticks 7 adapted to carry the hanks of fibre to be dyed or otherwise 55 treated by the liquor in the vat 1. A rail 8 is adapted to lie over the depressions

6 to hold the sticks in position, and this rail 8 can be locked by means of finger-pieces 9 turning on pivots 10.

When the to and fro horizontal motion 60 is desired, pinion 43 is slid into gear with the fully toothed wheel 44 and the frame is connected to a reciprocating connecting rod 11, by a detachable pin 12 passing through the bracket 13 on the frame 3 and said connecting rod 11. Frame 3 is first lifted to a certain level to allow of the insertion of bearing rollers 14 on spindles 15 in bearings 16 on the top of the sides of the vat 1. A step 17 may be arranged at the 70 side of the vat 1 to allow of this operation being conveniently performed.

The bearing rollers 14 support a longitudinal cross rail 18 having lateral brackets 19 integral with it, adapted to be connected to eyes 20 on the frame 3 by detachable pins 21 connected to short chains 22 on the frame to prevent accidental loss. The frame 3 can further be guided in its to and fro movement by means of bars 23 fastened detachably by set screws 24 on the side of the vat and slidably in bearings 25 on the frame 3.

When it is considered by the machine operator that the frame 3 has been reciprocating horizontally for a sufficient length of 85 time, the pin 12 is removed, as also the rollers 14 and then the guide bars 23 and next the pinion 43 slid out of gear. Rope 4 can then be connected by hook 26 to an eye 27 on the rails 18, said rope 4 being adapted to 90 be connected by a similar detachable hook to a pin on either the pulley 28 or 29 on shaft 30. For the purpose of a continuous up and down reciprocation of the frame 3, the cord 4 is attached to the periphery of 95 pulley 28.

The difference in speed of the vertically reciprocating frame when moving up and down can be obtained by means of gears or drums of different diameter. In a preferred arrangement, however, the high speed is obtained in one direction by allowing the driving shaft to rotate freely by reason of the weight of the frame connected to it, so 100 that the yarn, at the fall of the frame, is raised off the sticks by the maximum resistance of the liquor created by the extreme velocity of the fall. For this purpose the shaft 36 mounted in bearings 37, on frame 2, is continuously rotated in one direction 110 only. On this shaft 36, which carries a worm wheel 38 driven by a worm 39 on a

shaft 40 having fast and loose pulleys 41, 42, are mounted gears 44 and 32. The gear 32 is toothed on a limited length of its periphery only. It is obvious that if pinion 43 is kept out of gear, the shaft 30 will rotate in one direction as long as pinion 31 engages with the toothed portion of a mutilated wheel 32 causing the rope 4 to coil itself on pulley 28 and thereby raise the frame 3; but as soon as the last tooth of the mutilated wheel 32 disengages itself from pinion 31, shaft 30 thus set free, will reverse under the weight of frame 3 and will thereby be lowered into the vat uncoiling the rope 4 from pulley 28 in its fall. When the toothed portion of the continuously rotating wheel 32 comes again to engage with pinion 31, frame 3 is again raised and falls back into the vat in the same manner and thus the differential up and down motion will continue as long as desired. If required, means may be provided to allow the guiding of frame 3 in vat 1 up and down, without later on interfering with the to and fro movement.

Should now it be desired to revert to the to and fro movement, the rope 4 is disconnected from the pulley 28, the pinion 43 is then slid into gear with the fully toothed pinion 44 on shaft 36. The shaft 30 then rotates continuously in the same direction.

The rotation of shaft 30 is communicated to a parallel shaft 45 through pinion gearing 46, 47. The shaft 45 has a bevel wheel 48 keyed to it which drives the bevel wheel 49 on shaft 50 which carries a disc 51 having a crank pin carrying the connecting rod 11, reciprocating this, whereby the frame 3 is moved to and fro in the manner previously described.

When it is desired to remove the sticks 7 from the frame 3, or remove frame 3 from the vat for any reason, the rope 4 is connected to a pin on the periphery of pulley 29 and shaft 30 is given a rotation so that the rope 4 is wound on pulley 29 and frame 3 is raised above the vat. Rails can then be slid in under the frame and this removed.

To lower the frame rope 4 is first coiled by hand round the periphery of pulley 29, in a direction opposite to that in which the shaft 30 rotates, and thus when the machine is set in motion, shaft 30 in its rotation uncoils rope 4, whereby the frame 3 is lowered into the vat. The rails 18 are detachable from the frame 3 so that they can be used with a number of frames.

It is obvious that a single driving mechanism as shown on the stand 2 can operate the movements of frames in a number of vats, that is to say that for instance to obtain the up and down motion, a rope or ropes 52 may pass along with or be connected to the rope 4, to connect to the rails 18 of the frame working in connection with

another vat. Again the vat 1 may be subdivided into a number of compartments in each of which a frame 3 may be arranged simultaneously or separately operated from the driving mechanism on the stand.

Similarly if the shaft 45 is run along a combination of separate vats or subdivisions of one vat, the to and fro horizontal motion is easily obtained by connecting each vat or each sub-division of one vat to shaft 45 through similar arrangements of bevel wheels 48, 49, shaft 50, disc 51, and rod 11.

I claim:

1. In a machine for the treatment of textile fibres, a liquor-carrying-vat, a closed perforated cage or a frame carrying fibre bearing sticks movable lengthwise of the vat when supported on bearing roller fitted transversely and detachably within the vat, and adapted to be moved vertically when the rollers are removed, means for first giving a to and fro motion under liquor, and means for giving at another time a up-and-down motion at a different speed up to the speed down, as stated.

2. In a machine for the treatment of textile fibres, a vat containing liquor, a closed perforated cage or a frame, means for imparting to said cage or frame first a to and fro motion lengthwise of the vat when supported on bearing rollers fitted transversely and detachably within the vat, means for giving at another time a up and down motion when freely suspended, and a continuously rotating shaft, adjacent the vat, for transmitting both motions, as stated.

3. In a machine for the treatment of textile fibres, a vat containing liquor, a closed perforated cage or sticks carrying frame, a detachable top-rail adapted to be fixed to the cage or frame and travel on flanged rollers when said cage or frame is reciprocated horizontally, or remain suspended when the rollers are removed and the cage or frame is operated up and down by one of two different motions, transmitted by one continuously rotating shaft, adjacent the vat, as stated.

4. In a machine for the treatment of textile fibres, a vat containing liquor, a closed perforated cage or frame with loose sticks carrying yarns, a top-rail detachably fixed to the cage or frame, said cage or frame having vertical supports projecting some distance from its bottom parts to keep the yarn or material clear of the bottom of the vat when reciprocated horizontally on rollers, or vertically when freely suspended, by a motion transmitted through a rope or chain and guide-pulleys by a drum oscillated about its axis in working connection with one of two different motions generating from one continuously rotating shaft, adjacent the vat, as described.

FELICE FRANCESCO LARIVEL.
